UNITED STATES PATENT OFFICE.

RAY NIKIRK, OF WORTH COUNTY, AND GLENN E. CATHCART, OF MANLY, IOWA.

RAILWAY STOP-SIGNAL.

1,326,284.

Specification of Letters Patent. Patented Dec. 30, 1919.

Application filed May 21, 1919. Serial No. 298,768.

To all whom it may concern:

Be it known that we, RAY NIKIRK and GLENN E. CATHCART, citizens of the United States, residing in the county of Worth, and at Manly, respectively, in the county of Worth and State of Iowa, have invented certain new and useful Improvements in Railway Stop-Signals, of which the following is a specification.

This invention relates to railway signals and has for its object the provision of a signal device in the nature of a sign which is adapted to be engaged upon a rail at any desired point, as for instance at some distance to the rear of a train which is standing still, the construction of the device being such that when engaged upon a rail its weight will hold the rail engaging portion in clamping relation to the rail so that accidental displacement of the device will be prevented.

An important object is the provision of a signal of this character which will be simple and inexpensive in manufacture, which may be quickly and easily applied to or disengaged from a rail, which will be efficient and durable in use, and a general improvement in the art.

With the above and other objects and advantages in view, the invention consists in the details of construction to be herein-after more fully described and claimed, and illustrated in the accompanying drawing, in which—

Figure 1 is a front elevation of the device applied to a rail, the rail being in section, and

Fig. 2 is a horizontal sectional view on the line 2—2 of Fig. 1.

Referring more particularly to the drawing, the numeral 10 designates a standard which is formed preferably of bar iron and which carries at its upper end a preferably metallic plate 11 bearing any desired legend such as "Stop", as shown on the drawing. This plate 11 may be secured to the standard 10 in any desired manner, as by means of suitable rivets. At its lower portion, the standard 10 has formed thereon a laterally deflected portion 12 which terminates in a downwardly extending portion 13 which is parallel with the major portion 10 and which has its end curved, as shown, to provide a jaw 14.

Pivotaly mounted on the lower end of the portion 13, as shown at 16, is a member

17 which has its major portion extending below the portion 12 of the standard 10 and which has the extremity of its major portion provided or formed with a right angularly extending handle 18. The other end of this member 17 is formed to provide a jaw 19 adapted to extend over the ball of a rail A and adapted for coöperation with the jaw 14. A coil spring 20 is connected with the portion 12 and with the adjacent end of the member 17 for normally holding the jaws together.

In the use of the device it will be seen that in order to engage it upon a rail it is merely necessary that the operator grasp the handle 18 and push downwardly thereon against the resistance of the spring 20 to move the jaw 19 outwardly away from the jaw 14, whereupon the device may be easily placed over the ball of the rail. The operator then releases the handle 18, whereupon the spring 20 will pull the jaw members together into engagement with the rail, after which the weight of the standard 10 and the plate 11 will aid in holding the jaws in firmly clamping relation upon the rail so as to prevent any accidental displacement of the device.

From the foregoing description and a study of the drawing it will be apparent that we have thus provided an extremely simple device which may be quickly and easily engaged upon or detached from a rail, and which is so constructed that its weight will insure its being held firmly upon the rail, the device of course bearing any desired warning legend.

We claim:

1. A device of the character described comprising a standard, a legend bearing plate on the upper end of the standard, a jaw formed on the lower end of the standard, a member extending transversely of and pivoted near the lower end of said standard, a jaw formed on one end of said member and coöperating with said first named jaw for clamping engagement upon a rail, a handle formed on the other end of said member, and a spring urging said jaws together.

2. A device of the character described comprising a standard having its intermediate portion offset at right angles and its lower end extending parallel with the upper end, the extremity of said lower portion being curved at one edge to provide a

jaw, a transverse member pivoted upon the lower portion of the standard and having one end curved at one edge to provide a jaw coöperating with said first named jaw for engagement upon the ball of a rail, a handle formed on the other end of and extending at right angles from said member, and a spring connected with said member and the laterally extending intermediate portion of said standard. 10

In testimony whereof we hereto affix our signatures.

RAY NIKIRK.
